UNITED STATES PATENT OFFICE.

LOUIS B. PRAHAR, OF BROOKLYN, NEW YORK.

DESIGN FOR A HAND-BAG FRAME.

SPECIFICATION forming part of Design No. 15,592, dated December 2, 1884.

Application filed September 10, 1884. Term of patent 7 years.

To all whom it may concern:

Be it known that I, LOUIS B. PRAHAR, of Brooklyn, in the county of Kings and State of New York, have invented and produced a new and original Design for Hand-Bag Frames, of which the following is a description.

Reference is to be had to the accompanying drawing, forming a part of this specification, which is an elevation of a hand-bag frame illustrating my design.

The leading feature of my design consists of an irregularly-corrugated surface.

A is a side of a hand-bag frame, which has irregular corrugations B in its surface.

I claim—

The design for a hand-bag frame herein shown and described, the same consisting of the irregular corrugations B in the frame A.
